APPARATUS FOR PHOTOGRAPHIC
REPRODUCTION

Joseph Gerald Brocton Halden, Loughton, England,
assignor to Ozalid Company Limited, Loughton,
England, a British company

Filed Feb. 12, 1962, Ser. No. 175,866
6 Claims. (Cl. 95—75)

The invention relates to photocopying apparatus and is especially concerned with apparatus for producing diazotype prints from transparent or translucent graphic originals.

In one example of such apparatus a master consisting of a drawing or the like on transparent or translucent material is brought into contact in superposed relation with a sheet of diazotype or other sensitised material, and exposed to a source of actinic light by feeding the master copy and the sensitised material past the light source by means of rollers, endless bands or belts or other conveying means.

Such machines are well-known and are theoretically capable of a comparatively high rate of output. In the feeding of sheets of sensitised material and master copies to the machine it is, of course, necessary to ensure that when exposed to the source of light the two are in correct register.

It has been customary for such machines to be fed by hand and it has then been found in practice that the rate of feeding cannot be commensurate with the working capacity of the machine; in fact it is quite usual for a machine to be fed in this manner at about only one-fifth or one-sixth of its potential capacity. The machine is thus employed wastefully, in that it is run at only a fraction of its potential speed if operator efficiency is to be maintained.

Diazotype machines can be designed to run at speeds of well in excess of 40 feet a minute, but survey has shown that even when a web of sensitised material is used instead of separate sheets, once a speed of about 20 feet a minute is exceeded, hand feeding becomes inefficient and consequent unacceptable wastage of material results.

It is an object of the present invention to facilitate the employment of photographic, especially diazotype, reproduction apparatus up to its potential capacity, in particular by enabling sensitised material to be fed into the apparatus as a continuous web or successive large sheets while eventually prints are delivered as cut sheets, the sensitised material and masters to be copied being meanwhile fed in a rate which may be commensurate with the potential capacity of the machine.

The invention comprehends machines which may be either wholly automatic or partly automatic and partly manually operated and capable of use either with a continuous web or separate large sheets of sensitised material.

The present invention provides a photocopying apparatus comprising means, at an exposure station, for exposing sensitised material, means for progressively feeding a web or succession of large sheets of sensitised material to an assembly station, means at a cutting station in the path of the sensitised material to the assembly station operative in response to control means each time a predetermined length of the web or of a large sheet has passed the cutting station, to cut the web or sheet transversely thereby to produce a succession of sheets of a predetermined length, means at the assembly station whereby the cut sheets and masters may be superposed on one another, and means for feeding the superposed sheets and masters through the exposure station.

Particularly to enable hand-feeding of masters, means

2

may be provided for temporarily arresting the cut sheets at the assembly station.

There may be means for longitudinally slitting the web or sheets, before or after cutting transversely.

5 In one embodiment of the invention there is adjacent the assembly station a detecting station having sensitised sheet detection means for detecting the presence of a sensitised sheet at the detection station, master detection means for detecting the presence at the detecting station or at another such station of a master to be copied, and means responsive to the detection of a sheet and of a master as aforesaid to assemble and feed the sheet and the master in superposed relation through the assembly station.

15 Preferably, in the embodiment just described the control means for the transverse cutting means is located along the feed path at a distance along the path from the cutting means equal to the length of sheet desired, and is arranged to be responsive to the arrival at the control means of the leading edge of the material to cause the actuation of said cutting means.

20 The control means for the cutting means preferably operates, when the web is cut, also to stop the feeding of the web to the cutting station. The feeding of the web may be restarted when the presence of both a master and a sheet is detected at the detecting station.

25 The sensing devices may comprise photoelectric cells which detect the presence of the leading edge of the web.

30 Thus, if it is desired to sever the web at, say, 8" intervals a photoelectric cell is located along the feed path at a distance of 8" from the guillotine blade, the photoelectric cell being so arranged that as the leading edge of the material is sensed by it the guillotine is operated transversely to sever an 8" length of web.

35 Subsequently, every time the leading edge of successive lengths of material is sensed by the photoelectric cell the guillotine is caused to operate.

40 If desired, the location of the control means along the feed path may be adjustable to vary the length of the sheets cut from the web.

45 Preferably the sheet detection means and the master detection means each comprise a photoelectric cell responsive to the presence of the leading edge of a sheet and a master respectively.

50 It is further preferred that when the leading edge of only a master or of only a sheet is detected at the detecting station the detection means which detects the master or the sheet operates to stop the feed of the master or the sheet respectively.

55 In one machine according to the invention there is a plurality of master detection devices spaced apart across the path of the masters respectively and responsive to a plurality of masters advancing side by side.

Two embodiments of the invention will now be described with reference to the accompanying drawings which illustrate more or less diagrammatically two machines embodying the invention and in which:

60 FIGURE 1 is a sectional view of a machine which is partly automatic, and partly hand-operated, and which may be modified as described hereinafter to render it completely automatic.

65 FIGURES 2 and 3 illustrate control assembly whereby predetermined lengths of sensitised material drawn from a roll are measured,

70 FIGURE 4 illustrates the disposition of slitting discs on a part of a slitting device, and

FIGURE 5 illustrates diagrammatically a sectional view of a second machine.

75 Referring now to the machine shown in FIGURES 1 to 4, and first more particularly to FIGURE 1, three conveyor units 1, 2 and 3 are arranged for conveying the

sensitised material from a roll 4 (of say 250 yds.) to a printing cylinder 5.

A roll locating device whereby the roll 4 can be positioned, comprises a pair of arms 6 pivoted at 7 and carrying at their opposite ends half bearings 8. The arms 6 are connected to double acting hydraulic cylinders 9, adapted in one position to raise the arms 6 and consequently the half bearings 8 away from core shafts 10 carrying the roll 4, so that in this position of the arms 6 the roll 4 may be readily placed in position for actuation of the cylinders 9 to move the arms 6 to their other position, in which the half bearings 8 are retained in contact with the said core shafts 10. Locating rollers 11 adjustably mounted on the arms 6 serve to position the roll 4 correctly.

The roll 4 rests on and is driven by a main drive roller 12, ensuring that the roll 4 is driven at constant linear speed notwithstanding variations in diameter as the web material is fed from the roll 4.

As the web material is fed from the roll 4, the hydraulic cylinders 9 thus ensure that the outer periphery of the roll is always maintained in contact with the drive roller 12.

The first conveyor unit 1 comprises two juxtaposed endless belts 13 and 14, defining a feed path along which the sensitised material is traversed to the second conveyor unit 2. The endless belts 13 and 14 pass around appropriately spaced guide rollers 15, 16, 17, 18, 19, 20, 21, 22 and 23 at least one, preferably roller 19, of which is a driven roller, moving the endless belts 13 and 14 in a direction to feed the sensitised material from the roll 4 to the conveyor unit 2 along the feed path extending from rollers 21 and 22, roller 23, roller 18 and roller 19.

The length of the feed path in the example under consideration is 30 inches, rollers 16, 20 and 23 being adjustable to alter the effective length of the feed path (shown in dotted lines) to 32 inches thus to enable all different standard sizes of sheets to be accommodated.

Sensitised material drawn from the roll 4 passes through a nip formed between rollers 24 and 25, through a guillotine device generally designated 26 to the aforementioned feed path defined by belts 13 and 14.

Rollers 24 and 25 serve as control rollers to measure the sensitised material as it is drawn from the roll 4, and are associated with worm drive devices 27 and 28, from which drive is imparted to the electrical limit switches. To cater for correct feeding of different standard sizes of sheets, roller 24 is dimensioned to make one complete revolution for every 10 inches of web travel and roller 25 is dimensioned to make one complete revolution for every 8 inches of web travel. The operation of the electric limit switches will now be more fully described with reference to FIGURES 2 and 3.

In FIGURE 2 the worm devices 27 and 28 are shown meshing respectively with worm wheels 29, 30 affording respectively gear reduction ratios of 3 to 1 and 4 to 1. Drive shafts 31 and 32 are driven through worm wheels 29 and 30 respectively and serve to actuate electric limit switches 33 and 34 respectively, which comprise respectively movable contact arms 35 and 36 (see FIGURE 3) each making one revolution for respectively 30 inches and 32 inches of web travel, fixed contacts 37, 38 and 39 for switch 33 and a fixed contact 40 for switch 34 governing circuits which are completed every time 10 inches, 15 inches, 30 inches and 8 inches of material is drawn from the roll 4. In all there are six fixed contacts indicated by the reference numerals 37, 38 and 39 and four fixed contacts indicated by the reference numeral 40.

A preselector switch 41 is provided readily to set the apparatus to feed predetermined lengths of web from the roll 4, the switch 41 comprising a movable contact 41a set by a manual control member 41b (FIGURE 2) readily accessible to the operator and four fixed contacts

42, 43, 44 and 45 controlling the four circuits aforementioned.

As the material drawn from roll 4 passes rollers 24 and 25, they are constantly rotated and through their associated gear drive actuate the limit switches 33 and 34. After passing rollers 24 and 25, the web is moved to the conveyor unit 1 through the guillotine 26, which extends for the full width of the machine feed path and which, as illustrated in this figure, comprises a stationary anvil block 46 and a vertically movable clamp bar 47 and cutting blade 48.

The clamp bar 47 and cutting blade 48 are normally held by spring means 49, slightly above the web material passing over the anvil block 46, but this movable assembly may be moved downwardly through the medium of pressure plate 50, first to clamp the web and hold it stationary between anvil block 46 and clamp 47, continued downward movement moving blade 48 to sever the web, the assembly then being returned to its normal position by the spring means 49. Movement of the clamp and blade assembly can be extremely rapid so that the moving web will not be bunched unduly while it is held on the anvil block.

To effect the downward movement of the movable assembly of the guillotine, a roller 51 mounted on an arm 52 pivoted at 53, bears on the pressure plate 50 the arm 52 being rocked about its pivot 53 by means of arm 54 connected to the armature 55 of a solenoid generally designated 60 every time the solenoid 60 is energised.

Solenoid 60 is in circuit with an electro-magnetic contactor controlled by the aforementioned limit switches 33 and 34 and preselector switch 41 so that, assuming switch 41 has been set for, say 10 inches, the solenoid will be energised every time 10 inches of material has been drawn from the roll 4 to actuate the guillotine to sever the web into 10 inch sections which are fed to the conveyor unit 1.

It will be seen, therefore, that with the guide path formed by belts 13 and 14 set at a length of 30 inches, three severed sections of web material each 10 inches long, will occupy the path before the first severed section reaches the second conveyor unit 2.

While it is preferred to slit the web longitudinally subsequent to the printing operation, for ease of illustration, a slitting unit is shown mounted adjacent to the web feed in rollers 21 and 22, such slitting device being generally designated 61.

As shown in FIGURE 4, which shows a part view across the width of the slitting device, there are slitting discs 62, 63, 64, 65 and 66 each mounted opposite a co-operating disc. The web passes between the slitting discs and the co-operating discs and as shown in FIGURE 1 the lower or co-operating discs are mounted on bent arms 67 pivoted at 68 and are moved by rotating cam members 69 into engagement with the slitting discs to slit the web.

The slitting discs and co-operating discs are arranged across the width of the web, which is a 40" web, so that two of the discs will operate to slit the web into three 13.3" strips, three of the discs will slit the web into 10" strips and one of the discs will slit the web into 20" strips.

The cam members 69 are so arranged that the co-operating discs are brought into engagement with only one of these aforesaid sets of discs at any one time. Thus there will be one set of cam members for each set of discs and co-operating discs so that the web can be slit into strips having the desired width.

In the case where strips 13.3" wide are produced, two double discs may be used, so designed as to remove two continuous strips each 1/2" wide from the web, so that strips of 13" web are produced.

The conveyor unit 2 comprises two sets of endless belts 70 and 71, belt 70 being located by guide rollers 72, 73 and 74 with a portion of the upper run of the belts pass-

ing over a suction tank 75, while belts 71 are located by guide rollers 76, 77 and 78 and arranged with its lower run disposed above of a portion of the upper run of belt 70 as illustrated.

To ensure the maintenance of correct relative speeds of travel between conveyor units 1 and 2, a chain drive is provided linking rollers 18 and 19 of conveyor unit 1 with roller 72 of conveyor unit 2, a free wheel device being incorporated in roller 72 to prevent conveyor 1 being driven faster than conveyor 2 (and to permit conveyor 2 to move when conveyor 1 is stationary).

Disposed beneath roller 76 of belts 71 and below the upper run of belts 70, is a second roller 79, rollers 76 and 79 forming trap rollers, the purposes of which will hereafter be described.

A series of trip contacts 80 are provided across the width of the endless belts 70 adjacent to the aforementioned trap rollers 76 and 79, the arrangement being such that, as the severed and slit material drawn from the roll 4 is delivered by conveyor unit 1 to the conveyor unit 2, the material is held flat on the belts 70 by means of the suction talk 75, so that the belt will carry the material along with it and as the leading edge of the material interrupts trip contacts 80, the web drive motor is automatically arrested or disconnected and the sections of sensitised material remain stationary with their leading edges under guide member 81.

The operator now positions three master copies to be printed over the three sections of sensitised material and either operates a manual control member (not shown) to re-start the web feed mechanism or slides the sensitised material with superposed masters to interrupt contacts 82 in series with contacts 80 to restart the web feed mechanism.

When the web feed mechanism is restarted, the sections of sensitised material, with their superposed masters, move to the trap rollers 76 and 79, which impart a frictional drive thereto and feed them between belts 70 and 71 to the third conveyor unit 3 and thence around exposure cylinder 5.

Conveyor unit 3 comprises a series of endless belts 83 passing around roller 78, which is a sectional roller with the sections carrying belt 71 rotating independently of the sections carrying belt 83 and around a conventional contact plate designated 84, belts 85 traversing the superposed masters and sections of sensitised material through the exposure cylinder 5.

The contact plate 84 fulfills two functions. It keeps the master sheet of sensitised material in superposed relation until they pass into the nip of exposure cylinder 5 and serves as a roller for one end of the belt 83.

A fully automatic machine embodying the invention may be constructed also as illustrated in FIGURE 1 and as previously described, with only minor modifications, the arrangement being such that, instead of providing for intermittent movement of the web material during its passage through the conveyor sections, the web is driven continuously.

As the web material moves continuously through the conveyor sections 1, 2 and 3 detector means (e.g. photo-electric cells) are provided, suitably located in the feed path of the material between the belts 13 and 14, to actuate master feed mechanisms when the leading edge of a severed and slit section of web has reached the said detector means. The master feed mechanism is so arranged that by the time the said severed and slit section of web has reached the upper run of conveyor belt 70, the masters are fed in registered and superposed relationship to the said web sections. In this form of the machine the guide member 81 and trip contacts 82 are redundant.

Referring now to the machine shown in FIGURE 5 of the drawings, 101 indicates a roll of sensitised material which is mounted in the machine casing, supporting

and locking arrangements being indicated by the reference numerals 102 and 103.

Any convenient mechanism may be provided for mounting and supporting the roll but as illustrated in the drawing it is mounted on a member 104 which may form a portion of the machine casing pivoted at 105 and carrying the supporting member 101 and locking means 102 and 103.

The pivoted member 104 is connected by the supporting bracket 102 to a winch mechanism generally designated 106. When it is desired to mount a roll of material in the machine the winch 106 is actuated to permit the member 104 to swing about its pivot 105 to a horizontal or substantially horizontal position resting on the ground. The roll 101 is then moved on to the supporting bracket 102 and locked in position thereon by the locking mechanism 103. After the leading edge of the roll has been threaded into the machine the winch mechanism 106 is actuated to move the supporting member 104 into the position illustrated in the drawing.

The machine proper comprises a pair of feed rollers 107 which may be spring pressed into engagement with each other as illustrated at 108, a guillotine device generally designated 109, a web slitting mechanism generally designated 110 and a feed path generally designated 111.

The sensitised material 112 drawn from the roll 101 after passing around appropriate disposed guide rollers and tracking devices diagrammatically shown at 113 and 114 passes into the nip of the feed rollers 107.

The feed path 111, as illustrated, comprises a pair of juxtaposed endless belts indicated at 115 and 116, the belts passing around appropriately disposed supporting rollers 117, 118 and 119 for the belt 115 and 120 and 121 for the belt 16. Tensioning rollers 122 and 123 may be provided as illustrated.

At the upper end of the feed path 111 adjacent to the supporting rollers 119 and 121 there are provided guide fingers as indicated at 124 and 125 defining a path 126 to registration rollers indicated at 127 and 128.

The exposure section of the machine is indicated generally by the reference numeral 129 and comprises a transparent cylinder 130 housing a source of actinic radiation (not shown) and a conveyor system consisting of a series of narrow endless belts 131 lapping around the cylinder 130 and supported by supporting rollers 132, 133, 134, 135, 136 and 137.

It will be seen, therefore, that the sensitised material 112 drawn from the roll 101 may be fed along the feed path 111 to the exposure section 129 of the machine.

To feed originals to be copied these are, as illustrated fed over the feed-board 138 of the machine to a conveyor system formed by juxtaposed moving endless belts 139 and 140 taking around appropriately disposed rollers 141 and 142.

At the outer end of the conveyor system there is provided a second pair of guide plates 143 and 144 which also define a path 145 to the registration rollers 127 and 128 the guide path 145 being superposed on the guide path 126.

Along the feed path 111 there are photo-electric cells which are each located at a standard sheet length from the guillotine device 109. The guillotine device operates when a cell located at a predetermined sheet length detects the presence of the leading edge of a sheet of material.

A selector switch (not shown) is provided to enable the operator to select the photoelectric cell which is to be operative during the working of the machine (i.e. to select the sheet length).

As an alternative to having a series of cells along the feed path 111 there may be one cell of which the position along the feed path may be varied.

There are two further photoelectric cells located in the guide paths 126 and 145 respectively and each being the same distance away from the nip between the registration

rollers 127, 128. The cell in the guide path 126 detects the leading edge of the sheet and the cell in the guide path 145 detects the leading edge of the master to be copied.

In the operation of the machine according to this invention the operator, as previously mentioned selects the appropriate photoelectric cell which operates the guillotine to chop the web into selected lengths and sets the slitting wheels to slit the web into selected widths.

On starting the machine the feed rollers 107 are caused to rotate and the endless belts 115 and 116 defining the feed path 111 commence moving.

The material 112 is thus drawn by the feed rollers from the roll 101 to pass through the guillotine device 109 and over the slitting device 110, where the web is slit longitudinally, and into the feed path 111.

As the leading edge of the material is detected by the photoelectric cell in the feed path the guillotine 109 is actuated transversely to sever the material 112 and the drive to the feed rollers 107 is interrupted.

The severed and slit section of web continues to be fed along the feed path 111 into the guide path 126 which leads to the registration rollers 127 and 128 at the assembly station. When the leading edge of the cut section of web is detected by the photoelectric cell in the guide path 126 the section is arrested by interrupting the drive to the feed path 111.

An original or originals is or are then fed along the feed path between the belts 139 and 140 into the guide path 145 and when the leading edge of the original or the leading edges of the originals is or are detected by the photoelectric cell or cells in the guide path 145 the belts forming the feed path 111 and the registration rollers 127, 128 are set in motion so that the cut sheets and the original or originals pass on into the exposure section 129 in superposed relation.

An important point to mention is that the sheets and the originals are not set in motion towards the exposure section until the leading edges of all the items across the width of the machine are at the assembly station.

When the registration rollers 127, 128 and the belts forming the feed path 111 are set in motion the feed rollers 107, 108 are also set in motion so that the action of the machine is continuous.

Alternatively, of course, the original may have been fed to the assembly station first or during the feed of the cut sheets of sensitised material, but in this case the photoelectric cell in the guide path 145 will stop the movement of the belts 139, 140 until the slit sheets are detected at their assembly point.

Thus it does not matter whether the slit sheets or the masters arrive first at the assembly station. The machine will not feed into the exposure section until both sets of photoelectric cells have detected the presence of their respective sheets or masters.

Thus it will be appreciated that the action of the two photoelectric cells, one in each of the guide paths 126 and 145 respectively, are so interconnected that the first of the cells to be sensitised by the arrival of a master or a sheet (dependent on which arrives first) acts to stop the feed of the article which it has detected, while the second cell on being sensitised acts to set the sheet and the master in motion through the registration rollers 127, 128 and the exposure section 129.

While reference has been made to the use of juxtaposed endless moving belts to provide the feed paths for the originals and sensitised materials it is to be understood that this is given merely as an example and that any other sheet transport devices may be employed such as for instance roller systems employing driven and idler rollers.

I claim:

1. A photocopying apparatus consisting of:
  - (a) at an exposure station means for exposing sensitized material
  - (b) means for progressively feeding a web of sensitized material to a cutting station
  - (c) cutting means at the cutting station operable to cut the web transversely
  - (d) control means which operates the cutting means each time a predetermined length of the web has passed the cutting station whereby to produce a succession of sheets each of a predetermined length
  - (e) means to feed the cut sheets in succession to an assembly station
  - (f) detection means to detect the arrival of the leading edge of a cut sheet at the assembly station
  - (g) means responsive to the detection of the arrival of the leading edge of a sheet by the detection means to stop the feeding means for the sheet
  - (h) means at the assembly station whereby the cut sheets and masters to be copied may be superposed on one another and
  - (i) means for feeding the superposed sheets and masters through the exposure station.

2. A photocopying apparatus as claimed in claim 1 and including at the assembly station master detection means for detecting the presence at the assembly station of a master to be copied, and means responsive to the detection of a sheet and of a master as aforesaid to assemble and feed the sheet and the master in superposed relation through the assembly station.

3. A photocopying apparatus as claimed in claim 1 in which the masters are superposed manually on the cut sheets and there is manually operable control means to operate the means to feed the superposed sheets and masters through the assembly station.

4. Apparatus as claimed in claim 1 in which between the cutting station and the assembly station there is a feed path for the cut sheets, which feed path has a length at least equal to the predetermined length of a cut sheet.

5. Apparatus as claimed in claim 4 in which the length of the said feed path is equal to the total length of an integral number of cut sheets and the cutting means is actuated by its control means when the feeding means for the cut sheets is inoperative.

6. Apparatus as claimed in claim 5 in which the control means and the length of said feed path are adjustable to vary the said predetermined length of the cut sheets.
